SELECTOR SWITCH FOR AUTOMATIC
TELEPHONES

Clarence E. Lomax, Chicago, Ill., assignor to Automatic Electric Laboratories, Inc., Chicago, Ill., a corporation of Delaware

Application September 5, 1946, Serial No. 695,011

8 Claims. (Cl. 179—18)

1

This invention relates in general to selector switches in automatic telephone systems, and more particularly to a novel circuit arrangement for a battery searching selector switch of the ten level twenty trunk type.

The object of this invention is to provide a novel controlling circuit which enables automatic selecting operations at maximum speed and with a high degree of accuracy and a circuit arrangement which lends itself to ready conversion for use in systems having different numbers of trunks.

A feature of the invention is the manner in which the cam relay and the off normal relay are arranged to alleviate the usual spring load on the release relay.

A further feature is the manner in which the cam relay and the off normal relay are arranged to effect application of dial tone to the line in seizure of the selector and to remove same so that it will not be heard at the end of the first digit.

Another feature is the manner in which both testing relays are arranged so as to operate simultaneously if they find an idle contact at the same time, the operation of one of the testing relays and the associated switching relay preventing operation of the switching relay associated with the other testing relay.

Other objects and features of this invention will become apparent upon reference to the specification and accompanying drawing.

Referring now to the drawing, the automatic telephone system thus illustrated incorporates the features of the applicant's selector circuit and includes a substation 1, finder switch 2, the battery searching selector circuit 3, connector 4, and a second substation 5.

The selector is connected to the finder 2 by conductors 133 to 137 inclusive and is controlled to operate by impulses transmitted from substation 1 in a well known manner to position the wipers 138 to 143 inclusive opposite a desired group of bank contacts which are connected by trunk lines to connectors such as 4, which further extends the call to subscriber 5. Essentially the battery searching selector circuit consists of a well known Strowger vertical and rotary switch having off normal springs 149, and cam springs 146 used in conjunction with a circuit including testing relays 10 and 20, switch through relays 30 and 40, line relay 50, release relay 60, cam release relay 70, vertical off normal relay 80, change over relay 90, vertical magnet 100, release magnet 110 and rotary magnet 120, their associated contacts and connections. The finder switch is of the type disclosed in application Ser. No. 702,846, filed October 11, 1946.

It will now be assumed that the calling subscriber at substation 1 wishes to extend a connection to subscriber 5. On removal of the receiver, a connection is initiated through the finder 2 in

5 a well known manner over connectors 133, 134, 135, 136 and 137. When this selector switch is thus seized, a loop circuit is closed for line relay 50 and a ground is connected by the finder to conductor 131, over contact 83 to relay 90. Relay 90 operates and at its contacts 92 opens a point in the operating circuit of magnet 120, and at its contacts 91 prepares a point in the operating circuit of vertical magnet 100 and prepares a self holding circuit. Relay 50 operates and at its contacts 51 closes an operating circuit to relay 60 over contacts 37, 47 and 51, and at its contacts 52 opens another point in the release magnet operating circuit. Relay 60 operates and at its contacts 61 places ground on conductor 137 to hold the finder 2, at its contacts 62 prepares a point in the holding circuit to relay 90 and the vertical magnet 100, at its contacts 63 opens a further point in the operating circuit of the release magnet 110, and at its contacts 64 completes an operating circuit to relay 70 over normally closed cam spring contacts 146. Relay 70 operates and at its contacts 71 opens a point in the busy tone circuit, at its contacts 72 completes a dial tone circuit over contacts 85', 72, 41, 31 and conductor 135, at its contacts 74 prepares an operating circuit for relay 20, at its contacts 75 prepares an operating circuit for relay 10, at its contacts 76 completes a circuit for permanent signal supervision over contacts 76, 22, 12, 39, 49, 121, 87 and conductor 148, and at its contacts 77 starts the dial tone generator. The selector is now prepared for receipt of impulses from substation 1, relays 50, 60, 70 and 90 being in the energized condition.

10 On receipt of the first break of the first impulse, line relay 50 deenergizes and at its contacts 51 opens the operating circuit to relay 60 and at its contacts 52 closes a point in the holding circuit to relay 90 and completes the circuit to vertical magnet 100 over contacts 37, 47, 52, 62 and 91. Vertical magnet 100 operates and elevates the wipers 138 through 143 inclusive one step whereby they are positioned in a well known manner opposite the first level of bank contacts in the associated contact field. Incident to the first vertical step, the vertical off normal springs 149 are closed and complete a circuit to relay 80. Relay 80 operates and at its contacts 81 removes ground from the lead 133 to the finder 2, at its contacts 82 places ground on the guard lead 134 to the finder, at its contacts 83 opens the operating circuit to relay 90, at its contacts 83' completes the aforementioned holding circuit to relay 90, at its contacts 84 prepares the busy circuit to the line, at its contacts 85' disconnects the dial tone cord from the line, at its contacts 85 prepares a point in the circuit to the release magnet 110, at its contacts 86 prepares a circuit to the rotary magnet 120 and at its contacts 87 opens the circuit to the permanent supervisory shelf lamp over lead 148. The

advantage in opening the all trunks busy lead 133 at contacts 81 lies in the fact that the ground will be kept from the all trunks busy lead if the finder releases and the selector does not. The vertical magnet elevates the wipers a number of levels relative to the number of impulses received. Relay 60 is slow to release and holds up during the pulsing, being aided in its energization during each make period of the incoming pulses. Relay 90 is also slow to release and is aided to hold during the series of incoming pulses on each break period of the impulses.

A short period after the cessation of impulses of the first digit, relay 90 releases, and at its contacts 91 opens its self holding circuit, and at its contacts 92 completes the self interrupting operating circuit to rotary magnet 120, over contacts 76, 22, 12, 39, 49, 121, 86 and 92. If all trunk lines on the selected level are busy the switch wipers will be stepped in a well known manner to the eleventh position, whereupon the cam springs 146 are operated to close the operating circuit to the busy tone generator and to open the operating circuit for relay 10. Relay 70 at its contacts 71 applies busy tone to the finder over line 135 and contacts 84, 11, 41, and 31, at its contacts 72 further opens the dial tone circuit to line 135, at its contacts 74 opens the prepared circuit to relay 20, at its contacts 75 opens the prepared circuit to relay 10, and at its contacts 76 opens the circuit to the rotary magnet. The calling party on receipt of the busy tone restores which opens the operating circuit to relay 50. Relay 50 releases and at its contacts 51 opens the circuit to relay 60. Relay 60 releases and at its contacts 61 removes ground from conductor 137 to the finder, at its contacts 62 further opens the circuit to relay 90 and magnet 100, at its contacts 63 completes a circuit to the release magnet 110 over contacts 37, 47, 52, 63 and 85, and at its contacts 64 further opens the circuit to relay 70. Magnet 110 operates and releases the switch thereby opening the operating circuit to relay 80. Relay 80 restores and the switch is then ready for a subsequent call.

If the selected level is not busy, the switch will stop rotating when either of the wipers 142 or 143 or both find an idle trunk with battery potential thereon. Assuming wiper 143 finds battery, a circuit will be completed for relay 20 over contacts 38 and 74. Relay 20 operates and at its contacts 21 completes an operating circuit to relay 40 over contacts 21 and 16, and at its contacts 22 opens the operating circuit to the rotary magnet 120. The rotary motion of the switch is stopped thereby. Relay 40 operates and at its contacts 41 and 43 opens the operating circuit to line relay 50, at its contacts 42 and 44 connects lines 135 and 136 from the finder to line 138 and 140 which are connected to the idle trunks of the first group of trunks of the selector, at its contacts 45 connects line 137 to line 143 and thereby extends the C lead through the selector, at its contacts 46 closes a temporary holding circuit for itself over contacts 61 and 46, at its contacts 47 opens a further point in the operating circuit of the release magnet 110, at its contacts 48 opens a point in the operating circuit of relay 10, and at its contacts 49 opens a further point in the operating circuit for rotary magnet 120. If the first tested trunk of the first group of trunks were found busy and the tested trunk of the second group of trunks were not busy wiper 142 would have been connected to battery potential on the first idle trunk

of the second group and relays 10 and 30 would have operated in the same manner as relays 20 and 40 were operated. It is evident that leads 135 and 136 would then be connected to leads 137 and 141. If both wipers 142 and 143 find battery they will try to operate simultaneously. Either relay 10 or relay 20 will operate first. Assuming relay 20 operated first it will effect operation of relay 40 which in turn opens the operating circuit to relay 10. Relay 10 will have operated, but relay 40 now operates to restore relay 10 before relay 30 is operated. The circuit operation if relay 10 were to operate before relay 20 is evident from the foregoing disclosure.

Assuming again that both test wipers 142 and 143 find battery, ground is connected over these wipers through the resistance of relays 10 and 20 respectively. Assuming relay 20 operated first. An operating circuit to relay 40 is completed as previously described. Relay 40 energizes and at its contacts 48 removes the ground to relay 10 and wiper 142. In this fashion the ground through relay 10 is removed from the test wiper and eliminates the possibility of the non-seized trunk testing busy to other switches.

Relay 50 restores as described above and at its contacts 51 opens the operating circuit to relay 60, and at its contacts 52 closes a point in the operating circuit for release magnet 110. Relay 60 releases after an interval and at its contacts 61 removes ground from conductor 137 to the finder, at its contacts 62 further opens the operating circuit to vertical magnet 100, at its contacts 63 further prepares the operating circuit to release magnet 110 and at its contacts 64 opens the operating circuit to relay 10. Relay 70 releases and at its contacts 71 closes one point in the busy tone circuit, at its contacts 72 further opens the dial tone circuit to the line at its contacts 74 opens the operating circuit to relay 20, at its contacts 75 opens the operating circuit to relay 10, and at its contacts 76 opens the operating circuit to relays 30 and 40. Assuming that relay 40 is the operated relay, it will be held up by a ground returned over wiper 143 and contacts 45 and 46 from the succeeding switch. The call is now extended through the connector and relays 40 and 80 are held energized.

Release of the switch is effected in a normal manner. When the called party hangs up ground is removed from wiper 143 by the connector 4 and relay 40 releases and at its contacts 41 and 43 prepares the line circuit of the selector for subsequent calls, removal of ground from wiper 143 and conductor 137 also causes release of the finder 2. Relay 40 at its contacts 46 further opens its self holding circuit, at its contacts 47 completes an operating circuit to release relay 110 over contacts 37, 47, 52, 63 and 85. Release relay 110 operates and effects release of the selector switch in a well known manner. The off normal springs 149 open the circuit to relay 80 which releases and at its contacts 81 reapplys ground to the ATB lead 133 to finder 2, at its contacts 82 removes ground from the guard lead to finder 2, at its contacts 85 opens the operating circuit to the release magnet and at its contacts 83, 84, 86 and 87 prepares the selector circuit for subsequent operation. The release magnet releases and the selector is restored to normal.

It is evident from the foregoing disclosure that this 10 level-20 trunk selector may be easily connected to a 10-10 or a 10-30 selector by

adding or removing sets of relays similar to relays 10 and 30 with the associated wipers and banks therefore.

While a particular embodiment of the invention has been described, it will be understood that various modifications may be made therein which are within the true spirit and scope of the invention.

What is claimed is:

1. In a telephone system, a trunk line terminating in a two-motion automatic switch, means for seizing said switch over said line and operating same, a source of dial tone, a set of off normal springs and a set of cam springs in said switch, a cam relay in said switch having its operating circuit controlled by said cam springs, an off normal relay having its operating circuit controlled by said off normal springs, said cam relay operated responsive to seizure of said switch over said line to connect said source to said line, said off normal springs operated responsive to an initial movement of said switch to operate said off normal relay, means responsive to an operation of said off normal relay to remove dial tone from said line prior to termination of the initial movement of the switch, a source of busy tone, and means for at times operating said cam springs to terminate the secondary movement of said switch and to connect said latter source to said line.

2. In a two-motion automatic switch having a set of off normal springs, a set of cam springs and incoming connections, a cam relay having its operating circuit controlled by said cam springs, an off normal relay having its operating circuit controlled by said off normal springs, said cam relay operated whenever said switch is seized over said incoming connections, two switch operating magnets having operating circuits arranged to operate said switch in its primary movement and its secondary movement respectively, said off normal relay operated when the switch is operated in its primary movement by one of said magnets, said cam relay and said off normal relay arranged in combination to control the operating circuit of the other of said magnets to move the switch in its secondary movement.

3. In an automatic switch as claimed in claim 2 in which said cam springs are operated at times during said secondary movement to open the operating circuit of said cam relay, means operated responsive to release of said cam relay to prevent further operation of said other magnet, means operated to release said switch, said cam springs being effective to prevent operation of said other magnet on operation of said release means.

4. In an automatic switch having contacts connected at times to negative battery potential, incoming connections, a set of cam springs, a cam relay operated responsive to seizure of the switch over said incoming connections, an operating circuit for said cam relay controlled by said cam springs, a plurality of testing relays, a plurality of switching relays, each of said plurality of testing relays associated with each of said plurality of switching relays, operating circuits for said testing relays and said switching relays prepared responsive to operation of said cam relay, means for moving a plurality of the test wipers of said switches over said contacts in search of an idle contact, each of said plurality of testing relays connected to each of said plurality of wipers, one

of said testing relays and its associated switching relays operated when its associated wiper engages a contact having a negative battery potential thereon, said one testing relay and its associated switching relay operated to prevent any other of said plurality of switching relays from operating while the said one testing relay is operated.

5. In an automatic switch having contacts connected at times to negative battery potential, a plurality of testing relays, a plurality of switching relays, incoming connections, operating circuits for said testing relays and said switching relays prepared responsive to seizure of the switch over said incoming connections, means for moving a plurality of the wipers of said switch over said contacts in search of an idle contact, each of said plurality of testing relays associated with one of said plurality of switching relays and one of said plurality of wipers, a plurality of said testing relays operated when the wipers associated with said plurality of testing relays simultaneously engage a contact having negative battery potential thereon, one of said testing relays and its associated switching relay operative to prevent the switching relays associated with the other of said plurality of operated testing relays from operating.

6. In a telephone system, a trunk line terminating in an automatic switch, means for seizing said switch over said line and operating same, a relay having a single winding, a relay circuit including said single winding energized to operate said relay responsive to seizure of the switch, a pulsing circuit in said switch for operating said switch in a stepping operation in response to incoming impulses, a second relay, circuit means for operating said second relay responsive to said stepping operation of said switch, contacts operated by said second relay for disconnecting said relay circuit from said seizing circuit and for connecting said relay circuit to said pulsing circuit to thereafter control the operation of said single winding relay over said pulsing and relay circuits during said stepping operation.

7. In an automatic switch as claimed in claim 6 in which said switch has means for causing a secondary movement of the switch, said secondary movement means including contacts closed responsive to said release of said single winding relay for operating said secondary movement means.

8. In a two motion switch as claimed in claim 2 in which said cam relay is in the operated condition to effect said operating circuit of the other of said magnets to cause said switch to move in its secondary movement, and means for operating said cam springs responsive to said switch reaching a predetermined point in its secondary movement to effect release of said cam relay, said cam relay thereby operated to control said operating circuit to prevent said other magnet from moving said switch further in its secondary movement.
